UNITED STATES PATENT OFFICE.

WILLIAM OTTO ARZINGER, OF NASHVILLE, TENNESSEE.

ROTARY DRIER.

1,278,288.

Specification of Letters Patent. Patented Sept. 10, 1918.

Application filed November 1, 1917. Serial No. 189,715.

To all whom it may concern:

Be it known that I, WILLIAM O. ARZINGER, a citizen of the United States, and a resident of Nashville, in the county of Davidson and 5 State of Tennessee, have invented a new and useful Improvement in Rotary Driers, of which the following is a specification.

My invention relates to improvements in rotary driers, more especially those driers 10 which are of the electric type, and it consists in the combinations, constructions and arrangements herein described and claimed.

An object of my invention is to provide 15 a rotary drier which is intended primarily for use with graphite refining machinery, one which will take the graphite which has been separated by a flotation process, and quickly and thoroughly dry the graphite.

A further object of my invention is to 20 provide a device which will not only dry the graphite, but which will cause it to split apart or disintegrate, so that any foreign matter contained in the body of the graphite will either be consumed or will be brought 25 into such condition that it may be easily extracted subsequently.

A further object of my invention is to 30 provide a rotary drier in which the progress of the material from one end to the other of the drier, is assisted by means of the particular form and position of the heating elements.

A further object of my invention is to 35 provide a drier having heating units which may be easily placed in position or removed.

A further object of my invention is to provide a drier having electric heating units which will bring the graphite to a high temperature in very quick time, thus causing it 40 to disintegrate and to be thoroughly dried.

Other objects and advantages will appear in the following specification, and the novel features of the device will be particularly pointed out in the appended claims.

45 My invention is illustrated in the accompanying drawings forming a part of this application, in which:

Figure 1 is a central sectional view through the drier.

50 Fig. 2 is a section along the line 2—2 of Fig. 1.

Fig. 3 is a section along the line 3—3 of Fig. 1.

Fig. 4 is a detail view of a portion of the 55 drier and one of the heating elements.

Fig. 5 is a sectional view of a portion of

the device at right angles to the longitudinal axis thereof, and

Fig. 6 is a diagrammatic view showing the manner of connecting the heating elements. 60

In carrying out my invention, I provide a cylinder which consists preferably of a metal outer casing 1, an intermediate lining 2 of a heat resisting material such as asbestos, and an inner member 3 disposed contiguous to said heat resisting lining. 65

The cylinder thus formed is provided with heads 4 and 5, respectively, the head 4 being flat on its inner side and being braced externally by means of braces 6. The head 5 70 is slightly dished at its inner side as shown at 7. Both of these heads have flanges 8 which extend over the end of the cylinder. The head 4 is provided with a threaded hub 4* arranged to engage a threaded sleeve 9 75 which is journaled in a bearing 10 carried by an upright 11. Extending through the sleeve 9 is a feed pipe 12.

At the opposite end of the cylinder, the head 5 is threaded to a sleeve 13 journaled in 80 bearings carried by a frame 15. The latter forms a housing for a worm wheel 16 which is driven by a worm 17 on the shaft of a motor M.

At one end of the cylinder is a series of 85 inwardly extending units like that shown in Fig. 4, a description of one of these units will suffice, since they are all alike. Each unit consists of a coil made by bending a strip of metal back and forth. This strip 90 of metal is shown at 18. One end of the strip is connected with the binding post 19 suitably insulated from the casing, and the other end is held by a bolt 20 which is also insulated. The various units are connected 95 up in series, as shown in Fig. 6, clear around the cylinder and at the end of the units on one side of the unit shown in Fig. 4 and adjacent thereto, there is another binding post (not shown), similar to the binding post 19, 100 these two binding posts being the means by which the current is supplied to the series of heating elements. The bolt 20 need not be a binding post, but if it should be desirable to break up the heating units into one or 105 more series each supplied by current, then one of these bolts 20 could be used as a binding post without departing from the spirit of the invention.

As will be seen from the drawings, there 110 are two groups of the series of units 18, these two groups being connected either in

series or in parallel, as desired. The units are separated by a partition 24 which is secured to the cylinder by means of lugs 21, spaces 23 being provided at the outer edges 5 of the partition for the passage of the heated mixture. A similar partition 24 divides the cylinder into compartments, one of which contains a series of inwardly projecting vanes 25, these vanes being disposed in angular relation with the axis of the cylinder, so as to propel the material forwardly, that is to say, from the right to the left end of the cylinder shown in Fig. 1. The individual units 18 are also spaced angularly with respect to the axis of the cylinder, this angle coinciding with the angle of the same, as shown in Fig. 1.

From the foregoing description of the various parts of the device, the operation 20 thereof may be readily understood. The drier is rotated by means of the motor M, as stated. Current is supplied to the heating units 18 from any suitable source (not shown). These units are highly heated. 25 The graphite is forced through the inlet pipe 12 in a plastic state, that is to say, the flakes of graphite which have been freed from their associated gangue by a flotation process which forms the subject of a co-pending application, have had the water removed partly but not entirely. The flakes, therefore, are wet and cohere into a plastic mass which continually drops into the rotary drier. This plastic mass coming in contact 30 with the highly heated resistance elements 18, is not only dried, but the graphite is disintegrated to a certain extent, and certain foreign matter contained in the graphite is consumed by the high heat. Other foreign 35 matter either burns to an ash or drops out of the graphite, due to the agitation and to the disintegration of the flakes. The material is propelled forward, as stated, by the angularly disposed units and vanes 25. In 40 this it is assisted by a suction fan (not shown) which is connected to the sleeve 13 at the exit end of the rotary drier. The fan, however, forms no part of the present invention, having been fully set forth in a co-pending application.

I desire to call particular attention to the fact that there is a sudden heating of the graphite. This causes the moist graphite to disintegrate, where a slow heat would 55 not. It also thoroughly dries the graphite so that the latter easily passes around the partitions 21 and 24. All the graphite which has not been thoroughly dried or disintegrated by the first group of heating units 60 is practically so by the second group, and then the graphite passes the partitions and is taken up by the vanes 25 and forced toward the end of the cylinder where it is drawn out by the suction created by the fan 65 (not shown),

Due to the fact of the provision of the heat resisting lining, only a very small portion of the heat escapes, the greater part of the heat being used in breaking up and drying the graphite.

70

I claim:

1. A rotary drier comprising a cylindrical casing, means for insulating the walls of the casing to prevent the escape of heat, means for delivering material to be heated 75 at one end of the casing, a series of electrical heating units at the inlet end of the casing, a series of vanes at the outlet end, said vanes being inclined angularly with respect to the longitudinal axis of the cylinder for 80 propelling the material to be heated, forwardly.

2. A rotary drier comprising a cylindrical casing, means for insulating the walls of the casing to prevent the escape of heat, 85 means for delivering material to be heated at one end of the casing, a series of electrical heating units at the inlet end of the casing, said series of electrical heating units projecting inwardly from the walls of the 90 cylinder and being arranged to propel the material to be heated, forwardly.

3. A rotary drier comprising a cylindrical casing having heat insulating walls, means for rotating the casing, means for delivering material to be heated at one end of the casing, a series of electrical heating units at the inlet end of the casing, said series of units comprising coils projecting inwardly from the walls of the cylinders and being 100 insulated therefrom, certain of said coils being connected up in series, and a series of inwardly extending vanes at the opposite end of the cylinder, said coils and said vanes being disposed at an angle to the longitudinal axis of the cylinder, whereby the material is propelled from one end of the cylinder to the other during the rotation thereof.

4. A rotary drier comprising a casing having heat insulated walls, an inlet at one end of the casing, an outlet at the other end of the casing, means for rotating the casing, a plurality of groups of electrical heating units at the inlet end of the casing, 110 said groups being separated by a partition having openings at its outer edges, a plurality of inwardly extending vanes at the opposite end of the cylinder, said vanes being arranged angularly with respect to the longitudinal axis of the cylinders for propelling the material forwardly, and a partition disposed between said vanes and one of said heating units, said partition having openings at its edges for the passage of the material.

5. A rotary drier comprising a casing having heat insulated walls, an inlet at one end of the casing, an outlet at the other end of the casing, means for rotating the 120

125

130

135

casing, a plurality of groups of electrical heating units at the inlet end of the casing, said groups being separated by a partition having openings at its outer edges, a plurality of inwardly extending vanes at the opposite end of the cylinder, said vanes being arranged angularly with respect to the longitudinal axis of the cylinders for propelling the material forwardly, a partition disposed between said vanes and one of said

heating units, said partition having openings at its edges for the passage of the material, each of the series of heating units being composed of an individual coil extending into the cylinder from the walls thereof and being insulated from the walls, each of said units being inclined with respect to the longitudinal axis of the cylinder.

WILLIAM OTTO ARZINGER.
